HANDCUFF

Filed Dec. 17, 1928

Inventor:
August Almqvist,
by *Berthold Blatt*
Attorney.

UNITED STATES PATENT OFFICE

AUGUST ALMQVIST, OF IDROTTSPATSEN, SWEDEN

HANDCUFF

Application filed December 17, 1928, Serial No. 326,535, and in Sweden January 3, 1928.

This invention refers to an automatic hand-cuff and is characterized by a shackle acted upon by a spring and pivoted at or near the nave-shaped end of the hand-cuff, the said shackle being maintained in entirely open position by a spring-actuated, pivoted pawl engaging a tooth on the nave and being disengaged from locking position by a pivoted trigger in the shape of a two-armed lever adapted to be acted upon by the wrist and the inner shorter arm of which at its free end being eccentric in relation to the pivot of the trigger and resting against the free end of the pawl for cooperating with the said end when the trigger is rotated. After the free end of the shackle, by the tooth being released, has entered into an opening at or near the other end of the hand-cuff by the action of the spring, it is locked automatically in the said position by another spring-actuated, pivoted pawl adapted to engage a hole corresponding to the width of the wrist, the free end of said shackle being provided with a series of such holes for the said pawl.

The advantage of this construction in relation to hand-cuffs hitherto used lies in the fact that the hand-cuff may only be pressed towards the wrist for causing the trigger to be acted upon and the hand-cuff thereby being automatically locked close to the wrist, independently of the width of same. The hand-cuff may be mounted in locked position on a person's wrist in a moment, before any resistance can be offered, and without any additional manual exercises. It is evident that these qualities of a hand-cuff may be very valuable as for example to patrolling police and the like. In case a chain with lock is mounted on the hand-cuff it may also advantageously be used in the conveyance of prisoners.

The figure shows a vertical sectional view of the hand-cuff constructed in accordance with my invention.

In the drawing which shows an example of a hand-cuff according to the invention *a* is a hollow intermediate part containing means which thereby occupy a protected position. A handle *b* is firmly connected with both ends of the intermediate part, the said handle

together with the intermediate part enclosing an opening adapted to the easy insertion of the tooth and the steady grasp of same. Close to or near one end of the intermediate part of a semicircular shackle *c* is mounted at the opposite side of the intermediate part in relation to the handle, the said shackle having its one end shaped as a nave *d* and being pivoted at *e*. For the said shackle there is an opening *a'* in the wall of the chamber *a*, the said opening being only wide enough to permit the shackle *c* to rotate sufficiently. A spiral spring *f* fixed to the pivot *e* at its one end is fixed to its other end at the inside of the nave *d* and strives constantly to rotate the shackle into closed position or maintain it therein (marked in the drawing by II). The nave *d* has a tooth *g* which when the shackle is in entirely open position (the full line position in the figure) normally is in engagement with a spring-actuated pawl *l* pivoted at *h* and provided at its middle part with a projection *h*. The pawl is made as an one-armed lever and may be released from its locking position by a trigger *n* adapted to be actuated by the wrist and pivoted at *m* and having the shape of a two-armed lever, whose shorter arm located in the intermediate part is shaped eccentrically in relation to the fulcrum.

The said shorter arm rests against the free end of the pawl *l*, and when the outer long arm of the trigger *n* is subjected to the pressure of a wrist the trigger rotates and swings the pawl *l* out of its locking position, whereby the tooth *g* is released, and by the tension of the spring *f* the shackle *c* swings immediately towards the intermediate part *a* and enters with its free end into an opening *p* in the opposite end of the intermediate part. Hereby the shackle moves freely towards the trigger which penetrates through a slot *o'* of the shackle. For enabling the rotation of the trigger a slot communicating directly with the opening *a'* is made for the long arm of the trigger in the wall of the chamber *a*. In this manner the shackle *c* with the intermediate part *a* will completely encircle the wrist. By a preferably concave shape of the intermediate part on the side facing the

shackle one obtains a shape corresponding to the wrist and which is well adapted for safely retaining the hand-cuff at the wrist.

In that end of the intermediate part containing the opening p a pawl q in the shape of a two-armed lever V is pivoted at r . A spiral spring s threaded on the said pivot and which with its one end is fixed to the nearest wall of the chamber a and with its other, 5 tangentially extending end is fixed round one arm of the pawl r , acts by its tension on the said pawl in such a manner that the tooth shaped end t of one arm of the pawl q directed towards the slot p constantly tends to be in 10 the path of the free end of the shackle c .

The tooth t has such a shape that the shackle when it locks may easily overcome the tension of the spring s , the tooth successively turning aside from the shackle with 20 its face resting obliquely on the inside of the shackle, and snapping into a hole of a series of holes u provided on the free end of the shackle. Thereby the tooth permits the movement of the shackle in one direction 25 only, namely inwards towards the intermediate part.

For enabling the pawl q to release the shackle c the arm of the said pawl located on opposite side of the tooth t in relation to 30 the pivot r is so lengthened that it projects through a slot v on the side of the intermediate part facing the handle b , where it ends in a projecting tip x bent in the transverse direction of the intermediate part in order 35 not to hurt the hand when the same grasps the handle. When the pawl q is in suitable locking position the arm provided with the projecting tip rests against one end of the slot v in order that the tooth t , even when 40 the shackle is in open position, may maintain its locking position without being able to move too far into the path of the free shackle end.

When the hand-cuff is to be removed from 45 the wrist or the shackle is to be loosened from its locked position one moves the tip x laterally (to the right in the figure) as far as the length of the slot v permits, whereafter the shackle c may be freely rotated on the pivot 50 e . If one then turns the shackle back as far as possible, the projection h on the pawl l snaps in under the tooth g , as the said projection constantly tends to be in the path of the tooth g on the nave d , on account of the 55 tension of a spring y fixed with its one end on the pawl l and with its other end to the nearest wall of the chamber a .

In order to prevent the person on whom the hand-cuff is mounted from actuating 60 the projecting tip x and thereby disengaging himself, the pawl q and also the projecting tip x may be locked in locking position by a locking piece a'' rigidly connected to a pivot z , and comprising two oppositely and radially projecting arms. When the pivot z

and also the locking piece a'' are rotated in clockwise direction according to the figure the said piece will rest against one arm of the pawl q so that the pawl is prevented from moving out of its locked position in case one 70 should try to act upon the projecting tip x . But in the position according to the figure the pawl q is able to be moved from its locking position by the projecting tip x .

The pivot z may be rotated only by means 75 of a key constructed especially for the said purpose and whose shape may be difficult to imitate.

All pivots mentioned above are located at 80 right angles to and between the opposite side walls of the intermediate part a . The pivot e must be secured against rotation as the tension of the spring y might otherwise slacken. For this reason the pivot may for example be fastened by square ends in the 85 walls. The other pivots, with the exception of the pivot a'' , need only be riveted sufficiently in order not to fall out. The pivot a'' may have turned ends at the fastening 90 points so that it may be easily rotated as in a bearing without being able to move axially.

Having now described my invention, what I claim as new and desire to secure by Letters Patent is:

1. An automatic hand cuff, comprising a 95 hollow casing, a shackle pivotally secured to said casing, and entering with its free end an opening in said casing, means for normally moving said shackle to closed position, a spring operated pawl acting on the shackle pivot to maintain said shackle in open position, wrist operated means for releasing said pawl and said shackle to occupy the closing position, and means in said casing for automatically locking said shackle in closing 100 position.

2. An automatic hand cuff, comprising a hollow casing, a shackle pivotally secured to said casing, and entering with its free end an opening in said casing, means for normally moving said shackle to closed position, a spring operated pawl acting on the shackle pivot to maintain said shackle in open position, wrist operated means for releasing said pawl and said shackle to occupy the closing position, and means in said casing for automatically locking said shackle in closing 105 position, said pawl and said operating means being inclosed in said casing.

In witness whereof, I have hereunto signed 110 my name.

AUG. ALMQVIST.
